UNITED STATES PATENT OFFICE.

BERNHARD BUDWEISER, OF CHICAGO, ILLINOIS.

GLOVE.

1,250,963.

Specification of Letters Patent. Patented Dec. 25, 1917.

Application filed December 11, 1915. Serial No. 66,251.

To all whom it may concern:

Be it known that I, BERNHARD BUDWEISER, a citizen of the United States, residing at Chicago, in the county of Cook and State of Illinois, have invented certain new and useful Improvements in Gloves, of which the following is a specification.

My invention relates to improvements in gloves, and has for its general object to provide an improved glove structure in which the fourchettes, or side-forming-portions of the fingers, all have direct, lateral integral attachment respectively to appropriate finger-back portions, and wherein each finger back portion is integral with a back-body portion; and wherein the plurality of pieces comprising the back-body are so arranged that their lines of juncture may take arbitrarily-selected lines of direction remote from the knuckle-covering part of the glove in arrangement to secure attractive ornamental effect and a very firm anchorage for the finger-back portions.

In the drawing, wherein I have illustrated an embodiment of my invention as a work glove—

Figure 1 represents a blank cut in one suitable fashion to provide the back-body portion and directly-attached finger-back and fourchette-forming portions;

Fig. 2 shows a pair of blanks such as are used complementally to the first mentioned blank for completing the provision of the back body, finger backs, and fourchettes;

Fig. 3 shows a partly completed association of two insert parts;

Fig. 4 shows the glove-back and fourchette parts in fully assembled condition, and

Fig. 5 shows exteriorly the back of the completed glove.

In the drawings, 10 indicates in general the main back blank and 11 and 12 indicate supplemental blanks, that, conjointly with the main blank, are to provide the back-body, finger-backs and six fourchettes. These-back-and-fourchette parts will be supplemented by any suitable palm piece (suggested in dotted lines at 13 in Fig. 1) and with a thumb structure for the completion of the glove, but my present invention has no bearing on the formation of the palm or thumb parts, and these structures may be widely varied in detail.

The main blank 10 provides a main back

portion 14 and, integrally connected therewith, two finger-back portions 15^a and 15^d, respectively to form the backs of the forefinger and little finger. These finger-back portions have integrally connected therewith, laterally, at their contiguous sides, the fourchette-forming portions 16^a and 16^d, respectively. From points approximately at the roots or crotches of the two finger portions 15^a and 15^d, a suitably shaped aperture 17 is cut in the back-body portion 14, and the fourchette forming parts 16^a and 16^d aforesaid are cut transversely to form edges 18^a, 18^d; the aperture 17 thus being preferably approximately triangular in shape, with side edges 17^a, 17^d converging on any desired straight or curved lines toward the wrist portion of the glove. The precise size and shape of the opening are determined arbitrarily, primarily accordingly to artistry of design, but the edges 17^a, 17^d should have a length materially in excess of the width of a glove finger.

Each blank, 11 and 12, that supplements the main blank, provides a finger-back portion, a back-body-insert portion forming a longitudinal continuation of said finger-back portion, and two fourchette portions constituting integral lateral extensions from both sides of the finger back portions. Thus, as best shown in Fig. 3, the two complementary blanks 11 and 12 provide respectively the finger backs 15^b and 15^c for the middle-finger and ring-finger; the complementary back inserts 14^b and 14^c, that jointly will fill the opening 17, and the fourchette pairs 16^b, 16^{b'}, and 16^c, 16^{c'}.

In assembling the stated parts the crotch extremities of contiguous fourchette portions 16^b and 16^{b'} are stitched together as at 20, and the body inserts 14^b and 14^c are united along their contiguous longitudinal edges by suitable stitching as at 21. The two inserts thus united are joined to the main blank, the crotch extremities of fourchette portions 16^{b'} and 16^{c'} being respectively stitched to the edges 18^a—18^d of the two fourchette portions 16^a and 16^d, respectively, at 22 and 22', (Fig. 4) and the edges of the body-insert portions 14^b and 14^c being stitched, as at 23, to the edges 17^a and 17^d of the back opening in the back body.

It will be observed that, as each fourchette portion is integrally connected along its longitudinal or major dimension with a

contiguous finger back portion, the fourchettes are inevitably located in proper relation to such finger back portions, and may be blanked out, in the die cutting of the 5 blanks, with great accuracy, and may be stitched to the adjoining parts with greatest assurance of the correct sizing and location of such fourchettes. It will also be noted that the provision of finger back extensions, 10 arranged as inserts filling the opening made in the integral back body, gives a long bias seam line for the union of the edge of each such insert to the body, thereby affording a firm and desirable union, greater in length 15 than the width of the finger back, and removed from the knuckle-covering portion of the glove, so that there is no tendency of the seams 23 to chafe the knuckles, and so that the seams are not directly subjected to 20 the stresses caused by flexing of the metacarpal-phalangeal articulations. Furthermore, the several seam lines running from the posterior portion of the back-body to the finger crotches, may be made on any divergent 25 straight or curved lines that may most artistically give ornamental value to the glove, as best shown in Fig. 5.

While I have herein described in some detail a particular embodiment of my invention it will be understood by those skilled 30 in the art that changes may be made in the specific embodiment thereof without departure from the spirit of my invention and within the scope of the appended claim.

Having described my invention, what I 35 claim is:

In a glove, a main element providing in connected relation, a back-body part, finger-back portions for the fore-finger and little finger, and fourchette portions for the adjacent 40 sides of the said fore-finger and little finger backs, the crotch ends of the fourchettes being extended to form tabs to provide material for the crotch seams, said back-body having formed therein an opening extending 45 wristward from the crotches of the fore-finger and little finger back portions; in combination with two complementary members, each of which comprises a finger-back portion, a back-body insert portion, and two 50 fourchette portions laterally extending from opposite sides of the finger back portions and integrally connected therewith, being extended to form tabs to provide material for the crotch seams, said main element and complementary members united with said several fourchette portions appropriately 55 stitched together in contiguous pairs at their crotch extremities, and said back-body-insert portions filling, and stitched into, the 60 opening in the back body.

In testimony whereof I hereunto set my hand in the presence of two subscribing witnesses.

BERNHARD BUDWEISER.
